UNITED STATES PATENT OFFICE.

MADELINE REISER PRUDHOMME, OF NEW YORK, N. Y.

CURLING-IRON.

No. 922,949.

Specification of Letters Patent.

Patented May 25, 1909.

Application filed April 8, 1907, Serial No. 367,075. Renewed April 13, 1909. Serial No. 489,723.

To all whom it may concern:

Be it known that I, MADELINE REISER PRUDHOMME, a citizen of the United States, residing at New York, in the county of New York and State of New York, have invented certain new and useful Improvements in Curling-Irons, of which the following is a specification.

My invention relates to curling irons and its object is to provide a curling iron which will curl or wave the hair in imitation of the natural wave of the hair.

Another object of the invention is to overcome the liability of injuring the hair by breaking or scorching or burning it and this object is attained by slightly pressing the hair between heated irons arranged so as to be non-contacting.

To these ends my invention is embodied in preferable form in the device hereinafter described and illustrated in the accompanying drawings.

In these drawings, Figure 1 is a side view; Fig. 2 is a section on line X—X of Fig. 1, and Fig. 3 is a rear view.

Referring to the drawings illustrating my invention, 1 and 2 represent the handles of the device, which handles are adapted to receive a sheathing or covering of wood, ivory, or similar material 3. This covering serves to protect the hand from the heat of the fingers of the iron, and it is tightened around the handles by means of the band 4.

At one end of the handle 1, fingers 5 branch outwardly from the center of the handle, thereby forming a space between the fingers. The handle 2 is bent at a right angle at 6 and then bent again at a right angle to form a finger 7 running in a direction parallel to the other fingers. The bend 6 of the handle 2 spaces the finger away from the fingers of the handle 1 and by spreading the fingers of the handle 1 outwardly from its center the fingers of both handles are spaced apart. In spacing the fingers they are spaced so as to be an equal distance from each other or at the angles of an equilateral triangle as shown in Fig. 5. The fingers are tapered at 8 to form points 9 at their ends. These points allow the fingers to be pushed through the hair without liability of pulling the hair or injuring the scalp. The handles are joined together by a pivot 10 and are adapted to work on the pincer principle. The pivoted finger 7 is so located with respect to the fixed fingers, as to move between

the same without contact against the other fingers.

The hair is caught between the fingers after they have been heated, and as the fingers are spaced apart, there is no danger of the hair being burned or scorched or broken and the hair is lightly pressed between the fingers to be curled to imitate the natural wave of the hair.

Having thus described my invention, what I claim is:

1. A curling iron consisting of two members, one of said members carrying a pair of fixed fingers and the other member comprising a single finger and pivotally connected to the first member and having its handle portion bent at an angle to the plane of the pair of fingers so as to space the single finger from the pair of fingers, said pivoted member being so limited in its movement as not to be movable into or across the plane of the pair of fingers, substantially as described.

2. A curling iron having a part provided with two fixed and separated fingers, a finger pivoted to said part and having its handle portion crossing the other fingers, whereby when the handles are moved apart the fingers will be also moved apart, said fingers being so mounted that one of said fingers will be outside of the plane passing through the other two fingers when the handles are in closed position and to be noncontacting in the operation of curling, substantially as described.

3. A curling iron having a handle, said handle having fixed fingers thereon and spaced outwardly from one another, a pivoted handle engaging said first handle and having a portion bent at a right angle to the said first handle and crossing the same and having a single finger which is thereby spaced from the fixed fingers and carrying the movable finger outside of the plane passing through the other two fingers when the fingers are in closed position, said single finger being parallel to the fixed fingers, said fingers all being substantially spaced one from the other, whereby the hair may be curled between the fingers without pressing or crimping action of the fingers upon the hair, substantially as described.

4. A curling iron having two fingers, a common handle for said fingers, a third finger, a handle for said third finger pivoted to the first handle, the gripping portions of said handles being spaced apart, a portion joining

the handle to the third finger and at right angles to said parts and extending across the other fingers so as to carry said third finger away from and opposite the space between the first two fingers in such position that the three fingers will be located at the angles of an equilateral triangle when in closed position, said third finger and the other fingers

being operable to move apart in non-intersecting paths by separating the handles, ¹⁰ whereby the hair may be curled by a non-pressing action, substantially as described.
